UNITED STATES PATENT OFFICE.

HENRY C. MAUL, OF DETROIT, MICHIGAN, ASSIGNOR TO THE MICHIGAN STOVE COMPANY, OF DETROIT, MICHIGAN, A CORPORATION OF MICHIGAN.

GRATE-BAR MECHANISM.

Application filed July 5, 1924. Serial No. 724,310.

To all whom it may concern:

Be it known that I, HENRY C. MAUL, a citizen of the United States, residing at Detroit, in the county of Wayne and State of Michigan, have invented certain new and useful Improvements in Grate-Bar Mechanism, of which the following is a specification, reference being had therein to the accompanying drawings.

10 This invention relates to a grate assembly for stoves or furnaces wherein a plurality of rockable grate bars are provided and to which it is desirable to limit the rocking of the bars, except at certain times when an excessive rocking is required to effect the dumping of the ashes, clinkers or fire.

15 The purposes of this invention are to provide an arrangement of parts wherein great facility is obtained for the assembling and 20 disassembling of the grate bars within the stove or furnace, and to further provide for the limiting of the movement of the said grate bars when agitated for the shaking down of ashes in the normal manner, whilst

25 provision is also made for the release of the said grate bars to admit of their being moved to a much greater extent when thought necessary or desirable.

A further object of the said invention is 30 to provide for the combination with a plurality of simultaneously movable rockable grate bars and a surrounding casing of an extension or shaft on one of the bars projecting through the sides of the casing for the re-

ception of a shaker bar or handle, of a stop 35 operable from the outside of said casing, said stop normally loosely engaging said shaft to limit its movement and adapted to be disengaged to permit its free movement;

40 a still further object being to effect such control of the movement of the shaft by the use of a reciprocable stop member adapted to be brought into and out of engagement with a laterally extending abutment on the shaft.

45 Still further objects subsidiary to and resulting from the aforesaid objects, or from the construction or operation of the invention as it may be carried into effect, will become apparent as the said invention is hereinafter further described.

In carrying the said invention into effect, I may provide in a stove or furnace a series of grate bars coupled or linked together for simultaneous operation and journaled within a casing, the forward journaling means

being preferably in the form of a member secured to the casing and having recesses therein for the reception of the trunnions of the grate bars, said members being provided with a locking plate movable to a position securing said trunnion against accidental displacement from said journal member, an extended shaft on one of the said grate bars projecting through one of the sides of the casing and having an abutment thereon normally engaged by a stop within the casing, which stop is movable to a disengaged position by means exterior to the casing. And I may provide a movable section in the casing contiguous to the said shaft whereby the removal of said section will free the said shaft so that the grate bars may be freely removed from the said casing, upon their release by the moving or removal of said locking bar. All of which is more particularly described and ascertained hereinafter, by way of example, having reference to the accompanying drawing, in which—

Figure 1 is a sectional plan of the lower part of a stove embodying the said invention, part of the casing being broken away to better illustrate the arrangement of parts;

Figure 2 is a sectional elevation taken on the line 2^x—2^x Figure 1;

Figure 3 is an elevation of the same, and

Figure 4 is a detail broken perspective view of part of the casing illustrating the stop mechanism.

Similar characters of reference indicate similar parts in the several figures of the drawing.

A base casting or casing 1 having mounted thereon a fire pot 2 is shown, beneath which fire pot are arranged grate bars 3, 4 and 5 provided with trunnions 6, 7 and 8 at opposite ends thereof, the rear trunnions being journaled in a member 9 within the back of the casing 1 and the forward trunnions journaled in a special member 10 in the forward part of the casing. This member is indicated as being provided with downwardly extending lugs 11 having laterally opening recesses 12 therein which receive the forward trunnions of the grate bars.

In assembling the said grate bars the rear trunnions are entered into their supporting casting and the forward trunnions entered laterally into the recess 12 of the journal member 10, in which position they are se-

cured by a locking plate 13 slideable upon lugs 14 on the said member 10, the said locking plate 13 being provided with lugs 15 which cooperate with the lugs 11 in embracing said trunnions when the said plate 13 is in its closed position, in which position it is adapted to be secured such as by a set screw 16.

17 are downwardly depending arms from 10 the forward trunnions of the grate bar, the said arms being coupled together by a bar or link 18 for simultaneous operation of the said bars, and to effect such operation the center grate bar is shown as having its trunnion 15 extended forwardly in the form of a shaft through the front of the casing 1 and provided with a squared end 19 for the reception of a suitable shaking tool.

This shaft or extension of the trunnion 7 20 is provided with a laterally extending lug 20 within the casing which lug is engaged by a stop 21 in the form of a member slideably mounted in a block 22 within the casing, the said stop having a recess 23 therein 25 of greater width than the lug or abutment 20 whereby the engagement therebetween is loose and permits the shaking of the grate bars to an extent limited by the difference between the width of the said abutment and 30 the recess. The stop 21 is also provided with a handle 24 which extends outwardly through an aperture 25 in the said casing 1, whereby the said stop may be actuated from the exterior of the casing to effect its withdrawal 35 from engagement with the abutment 20 and to thereby permit the operation of the grate bars to a much greater extent so that the dumping of the stove or furnace may then be effected.

40 The front of the said casing 1 is further shown as being provided with a removable section or plate 26 secured in position by a set screw 27, the said casing and plate being provided with co-acting recesses 28 and 45 29 together forming an opening through which the shaft 7 passes. The removal of the said plate 26 releases the said shaft in so far as its relation to the casing is concerned, so that the grate bars may be easily 50 removed upon the withdrawal of the locking plate 13 from its locking position on the trunnions of the grate bars as will be readily understood.

55 The arrangement suggested is particularly applicable and convenient for stoves and furnaces such as of the type used in the heating of small buildings and admits of the ready renewal of the grate bars when necessary as well as their original assembling 60 in the stove or furnace in the course of construction; and the simple and effective arrangement of means controlling the movement of the grate bars permits the normal shaking thereof in a definitely determined 65 manner calculated to prevent undue loss of

fire or material from the grate, or the fouling of the grate bars by coal or clinkers but permitting when required the thorough dumping of the contents of the fire box of the stove or furnace.

70

This invention may be developed within the scope of the appended claims without departing from the essential features of the said invention, and it is desired that the specification and drawing be read as being merely illustrative and not in a limiting sense, except as necessitated by the prior art.

75

What I claim is:—

1. In a stove, in combination, a casing 80 having a front wall, a plurality of co-acting grate bars mounted in said casing, a shaft extension on one of said bars projecting beyond the front wall of said casing, and a stop slideable in a lateral direction against the inner face of the casing front wall normally limiting the rotation of said shaft, said stop having a portion slideable in the front wall of said casing.

85

2. In a stove, in combination, a casing 90 having a front wall, a plurality of co-acting grate bars mounted in said casing with one of said bars projecting through the casing front wall and a reciprocable stop against the inner face of the casing front wall slideable into loose engagement with a part of said projecting grate bar to limit oscillation of said grate bar and when retracted permit free rocking of said grate bar.

95

3. In a stove, in combination, a casing 100 having a front wall, a plurality of co-acting grate bars mounted in said casing, a shaft extension on one of said bars projecting beyond one of the walls of said casing, an abutment on said shaft, and a forked stop on one side of the casing front wall and operable from the opposite side of said casing front wall for engagement with said abutment.

105

4. In a stove, in combination with a casing, a grate bar assembly comprising a plurality of linked rockable bars journaled at the back of said casing, a journal member in the forward part of said casing and adapted to receive said bars by lateral movement of said bars therein, a movable locking plate slideable laterally against said casing for receiving said bars in said journal member, and an operating shaft on one of said bars extending through the front of said casing.

110

5. The combination according to claim 4, wherein the front of the casing is provided with a removable section contiguous to the shaft whereby the removal of the shaft from the casing is facilitated.

115

6. Means for supporting a series of rockable grate bars in a furnace casing, said means comprising a rear journal member 120

125

130

for the rear ends of the grate bars, angular lugs for the front ends of said grate bars, a slideable locking plate, and angular lugs on said slideable locking plate to cooperate with 5 the first mentioned lugs in forming a journal support for the front ends of said grate bars.

7. Grate bar supporting means as called for in claim 6, wherein the first mentioned 10 lugs are on a front journal member support-

ing said slideable locking plate, with said rear and front journal members supported from said casing.

In testimony whereof I affix my signature in presence of two witnesses.

HENRY C. MAUL.
